UNITED STATES PATENT OFFICE

148,829

DESIGN FOR A SNOW SLED OR THE LIKE

John L. Turner, Old Saybrook, Conn.

Application December 6, 1945, Serial No. 124,426

Term of patent 14 years

(Cl. D34—15)

To all whom it may concern:

Be it known that I, John L. Turner, a citizen of the United States, residing in Old Saybrook, county of Middlesex, State of Connecticut, have invented a new, original, and ornamental Design for a Snow Sled or the like of which the following is a specification, reference being had to the accompanying drawings forming part thereof.

In the drawings:

Fig. 1 is a top plan view of a snow sled showing my new design;

Fig. 2 is a side elevational view thereof.

I claim:

The ornamental design for a snow sled or the like, as shown.

JOHN L. TURNER.
